(57) **CLAIM**

The ornamental design for a container lid, as shown and described.

DESCRIPTION

FIG. 1 is a perspective view of a container lid emphasizing a top surface of the container lid.

FIG. 2 is a perspective view of a container lid emphasizing a bottom surface of the container lid.

FIG. 3 is a front view of a container lid, the rear view of the container is a mirror image thereof.

FIG. 4 is a left end view of a container lid, the right end view of the container lid is a mirror image thereof.

FIG. 5 is a top view of a container lid.

FIG. 6 is a perspective view of a container lid in an alternate environment emphasizing a top surface of the container lid.

FIG. 7 is a perspective view of the container lid of FIG. 6 emphasizing a bottom surface of the container lid.

FIG. 8 is a top view of the container lid of FIG. 6.

FIG. 9 is a front view of the container lid of FIG. 6.

FIG. 10 is a left end view of the container lid of FIG. 6.

FIG. 11 is a right end view of the container lid of FIG. 6; and, FIG. 12 is an enlarged cross-sectional view of the container lid taken along line 12—12 of FIG. 5 and line 12—12 of FIG. 8.

The broken lines in the above-referenced figures do not form a part of the claimed design.
